DESIGN FOR A KEY RING SCREW DRIVER

Thomas C. Crowley, Jackson Heights, N. Y.

Application January 17, 1939, Serial No. 82,384

Term of patent 3½ years

To all whom it may concern:

Be it known that I, Thomas C. Crowley, a citizen of the United States, residing at Jackson Heights, Long Island, in the county of Queens and State of New York, have invented a new, original, and ornamental Design for a Key Ring Screw Driver, of which the following is a specification, reference being made to the accompanying drawing, forming part thereof.

Figure 1 is a front elevation of a key ring screw driver showing my new design.

Figure 2 is a cross section on line 2—2 of Figure 1.

Figure 3 is a view looking toward the edge having an opening forming a bottle cap remover.

I claim:

The ornamental design for a key ring screw driver, as shown.

THOMAS C. CROWLEY.
